UNITED STATES PATENT OFFICE

GLEN J. ARTHUR, OF ROCK ISLAND, ILLINOIS

NURSERY CHAIR

Application filed December 20, 1930. Serial No. 503,782.

The present invention relates to a nursery chair and comprises among its objects the provision of a chair of this character which will fold into a minimum of space; the provision of a chair which is easily foldable and yet is not readily operable by a child sitting therein; to provide in a chair of the character indicated readily detachable means for supporting collapsible and destructible containers; to provide a chair of the character indicated which, when the cover for the seat opening is put down into place, will have quite the appearance of an ordinary chair; to provide a chair which is simple and inexpensive to manufacture, may be sold at a reasonable price, and yet will be adapted for various uses; and such further objects, advantages and capabilities as will hereafter appear and as are inherent in the construction disclosed herein. The present invention further resides in the combination, construction, and arrangement of parts illustrated in the accompanying drawings, and, while I have shown therein what is now considered the preferred embodiment of this invention, I desire this disclosure to be understood as illustrative only and not as limiting my invention.

In the drawings annexed hereto and forming a part hereof, Fig. 1 is a front elevation of my new construction; Fig. 2 is a side elevation of the same; Fig. 3 is a fragmentary side elevation of this chair in partly folded condition; Fig. 4 is a perspective view of a guard which is attachable to and detachable from the seat of the chair; Fig. 5 is a perspective view of a saddle which is attachable to and detachable from the rear portion of the seat of the chair and may be adjusted forwardly and rearwardly to vary the size of the opening therein; Fig. 6 is a perspective view of a ring which is insertable into the hole in the seat of the chair and which serves to hold the collapsible container in distended condition; Fig. 7 is a rear edge view of a portion of the chair seat, taken in the direction indicated by the arrows on line 7—7, Fig. 8; Fig. 8 is a plan view of a portion of the chair seat intended

to illustrate the manner of mounting the trap door of the seat.

Reference will now be made in greater detail to the annexed drawings in which a pair of loops 1 and 2, hinged together at 3, 55 form the legs for supporting the seat. On the under side of the seat are a pair of metal straps 5, provided at one end with eyes 6 and at the opposite end with hooks 7. The upper cross bar of the loop 2 is provided 60 with portions which are reduced in width and about which the eyes 6 fit. These eyes and reduced portions cooperate to hold this upper cross bar in proper position laterally of the chair. The upper cross bar of the 65 loop 1 is placed within the hooks 7 so that the parts will be held in properly assembled relation to support the seat 4. Pivottally mounted on the loop 2 is a latch 8 whose purpose will be referred to hereinafter. 70

The seat of the chair is provided substantially centrally with an opening which extends therethrough and which, as illustrated most clearly at 9 and 10 in Fig. 3, has a stepped wall, that is, the opening is of decreasing diameter from the top towards the bottom and is provided with a plurality of shoulders. The trap door 11 is provided at its rear edge with an extension 12 which fits within an opening in the upper portion of 80 the seat 4. This extension 12 is slotted in a plane parallel to the flat upper surface of the trap door and about midway between its two faces. Nails 13 are driven into the seat 4 to form an axis for the trap door 11 to 85 turn about. The slot in the rear edge of the extension 12 is brought into registry with these nails 13 and then the trap door is shoved until the nails are approximately at the inner extremity of this slot. A wedge 14 90 is then glued into this slot to prevent the trap door 11 from being removed from the nails. These nails therefore form a portion of the hinge for the trap door, the inner extremity of the slot in extension 12 95 forming the other portion thereof. The rear portion of the opening in the seat extends entirely through the same to permit the extension 12 of the trap door to swing downwardly therein so that the trap door 100

may occupy the position shown in Fig. 2. As illustrated in this figure the trap door 11 rests against the back 15 of the chair.

A U-shaped frame member 16 is pivoted 5 at 17 to the seat 4 and has the back 15 secured between the extremities of the U-shaped member. The lower cross bar of this member cooperates with the latch 8 in preventing the chair back from swinging 10 forwardly when it is not desired that it do so. A pair of posts 18 are pivoted to the seat 4, as indicated at 19 and, as shown in Figs. 2 and 3, these remain substantially parallel at all times to the U-shaped frame 16. 15 The upper ends of members 18 are hingedly connected to the arms 20 of the chair. These arms have pivotal connection at 21 with the arms of the U-shaped frame 16. Therefore, when the latch 8 is unlatched 20 and the chair back is pushed forwardly, the arms 20 also go forwardly and carry the upper ends of the posts 18 with them, as illustrated in Fig. 3.

Means for connecting the posts 18 to the arms 20 comprise brackets 22 provided with 25 slots 23 for the reception of pivot bolts 24 which pass through the slots 23 and the posts 18. The upper end of each post 18 is provided with a notch 25 for the reception 30 of a projection 26 formed on an arm of the bracket 27 which extends inwardly across the post 18, the bracket being secured to the under side of the tray 28. The two brackets 27 serve as guiding means for the 35 tray when the same is placed upon the forward ends of the arms 20 and shoved backwardly. It will therefore be seen that when the tray is put into the position shown in Fig. 3 and is shoved backwardly until the 40 tray, posts 18, arms 20 and the back occupy the positions shown in Fig. 2, it will be impossible to remove the tray and therefore impossible for a child to release itself from the chair. In order to increase the 45 certainty that the child will remain in the chair, the latch 8 is turned down into the position shown in Fig. 2 and this will then prevent the chair back from being moved forwardly so that the tray can be released. 50 The ring 30 is provided with an inwardly and downwardly directed flange 31 designed to overlap the upper edge of the containers which are placed in the detachable conical shaped waterproof bag 32. This bag is 55 provided with a stiffening ring at its upper edge as indicated at 33. This ring rests upon the shelf 9 and supports the bag 32 in place as illustrated in Figs. 1 and 2. When the trap door 11 is closed, as illustrated in 60 Fig. 3, it rests upon the upper shelf 10 and fits entirely within this opening so that the upper surface of the seat is quite smooth. The ring 30 is provided with openings 34 and 35, as illustrated most clearly in Fig. 6. 65 The saddle 36 is provided with downwardly

extending lugs 37 which are arranged in suitable openings 34 so that the size of the internal opening in the ring will be suitable for the child which is to use the chair. A suitable guard or shield 38 which is concavo-convex in form, as shown in Fig. 4, is provided with a forwardly extending arm 39 from which depends a lug 40 which is adapted to be inserted into the opening 35 of the ring 30 and into a corresponding opening in the forward portion of the seat 4, illustrated in dotted outline at 41 in Fig. 3. The ring 30, saddle 36 and guard 38 are all made of readily flexible rubber and therefore do not hurt the child, when being used. Mention should probably also be made of the fact that when the ring 30 is in use it rests on the shelf 10 against which the trap door rests when the chair is folded. The ring 30 is made of just the right size to fit within the upper large portion of the opening through the seat of the chair. The sides of the guard 38 are readily flexible so that, though they contact with the delicate skin of the inside of the child's legs they do not 90 chafe nor injure the child. Also, the upper portion of the guard rests against the abdomen of the child and therefore tends to prevent the child from leaning forwardly, though the arm 39 is not sufficiently rigid to prevent the guard 38 from being tilted 95 forwardly under pressure.

Mention should have been made of the stops 42 which limit the backward motion of the upper end of the posts 18. The slots 23 permit a more complete folding of the chair since the pivots 24 slide backwardly in these slots when the chair is collapsed beyond a certain point. This is due to the fact that the pivots 19 and 24 are not as far apart as the pivots 17 and 21. There is therefore quite a decided cooperation between the slots 23, pivots 24, notches 25 and lugs 26, in the holding of the tray 28 in position.

It is of course understood that the specific description of structure set forth above may be departed from without departing from the spirit of my invention as set forth in this specification and the appended claims.

Having now disclosed my invention, I claim:

1. A nursery chair including a seat and a retaining ring of resilient material, said seat having a stepped opening therethrough, the retaining ring being of a size and shape to fit in said opening and rest on a step thereof and having a downwardly extending flange around its inner edge to project below the step on which the ring rests.

2. In a nursery chair, a seat having a substantially central opening therethrough, a saddle conforming approximately to the shape of the rear portion of the seat opening, said saddle having downwardly ex-

tending lugs for adjustment purposes and said seat having openings to cooperate with said lugs in the forward and rearward adjustment of said saddle.

5 3. In a nursery chair, a seat having a substantially central opening therethrough, a retaining ring mounted in said opening and having its upper surface substantially flush with the upper surface of the seat, said ring
10 having a laterally extending flange provided with adjustment openings and a saddle having downwardly extending lugs movable from some of said openings to others thereof for adjusting the effective
15 size of the seat opening.

4. In a nursery chair, a seat having an opening therethrough provided with a stepped wall, said opening having a rearward extension, and a closure member for
20 said opening having a rearward extension pivoted in the rearward extension of the seat opening.

5. A guard for a nursery chair comprising an elongated concave flexible article of read-
25 ily flexible rubber provided with side walls extending in a direction approximately parallel to the longitudinal dimension of the guard, said guard having an arm extending outwardly away from the convex wall
30 thereof.

In witness whereof, I hereunto subscribe
my name to this specification.

GLEN J. ARTHUR.
